DISCHARGING RECEPTACLE

Gérard Lapierre, Montreal, Quebec, Canada, assignor of one-third to Gabrielle Bernier, Montreal, Quebec, Canada

Application June 17, 1937, Serial No. 148,745

6 Claims. (Cl. 221—62)

The present invention pertains to a novel receptacle and particularly to an appliance thereto for discharging the contents. The invention is applicable especially to containers of paste and

5 powder such as tooth paste, tooth powder, face powder; soap powder and the like. The invention is useful in connection with a permanently supported receptacle or one that is comparatively small and usually held in the hand, such as a

10 tube of tooth paste or a can of tooth powder.

The invention embodies generally a ported closure adjacent to which is slidably mounted a ported valve plate. The two ports or openings are adapted to register to provide a free outlet 15 from the receptacle but are normally closed with respect to each other through the action of a spring tending to move the valve plate rearwardly or to the closed position.

More specifically, an object of the invention is 20 to direct sluggish or compressible materials, such as powders and pastes, towards the outlet and to prevent them from being compressed and accumulated into the ports of the closure and valve plate. This object is accomplished by 25 means of an enlargement formed on the valve plate at the rear end of the opening therein, and providing this enlargement with a surface sloping from the rear end of said port in the forward direction and away from the closure. 30 The sloped surface acts as a wedge that forces material to and through the registering ports when the valve plate is moved forward. By this means, not only is the material positively fed through the ports but is prevented from compressing or otherwise accumulating therein to 35 interfere with the free action to the device.

The invention further embodies a simple and 40 convenient means for normally closing the ports as above stated. A stem extends rearwardly from the enlargement and through the wall of the receptacle and is formed externally with a button. A coil spring is mounted between the button and the receptacle and is tensioned to draw the valve plate rearwardly to its closed position. The valve plate is moved forwardly to open position by 45 manual pressure of the button against the action of the spring.

The invention is fully disclosed by way of example by the following description and in the accompanying drawing, in which

Figure 1 is a longitudinal section of the closure end of the device in open position;

Figure 2 is a similar section of the device in closed position;

Figure 3 is a plan view of the closure end;

Figure 4 is a side elevation, and

Figure 5 is a section on the line 5—5 of Figure 1.

Reference to these views will now be made by use of like characters that are employed to designate corresponding parts throughout.

In Figures 1 and 2, the numeral 1 designates the body of a receptacle for tooth powder, face powder, soap powder or the like. The receptacle may be a wall receptacle which is usually mounted with its outlet downward, as illustrated herein, or it may be a small container held in the hand, such as a tube of tooth paste or a can of tooth powder. Accordingly, the end illustrated 10 in the several figures may be either the top or the bottom of the receptacle, according to the position in which it is held. For the purpose of description, it will be identified as the closure end.

The closure end of the receptacle is preferably reduced in the form of a neck 2 which may be circular, square or of any other desired shape. Across the free extremity of the neck is formed a closure plate 3 either as a separate member 25 attached thereto or a part integral therewith. The only outlet from the container through the plate 3 is an opening 4 through the plate as clearly illustrated in Figures 1, 2 and 3.

On the inner surface of the closure 3 is slidably mounted a valve plate 5. The valve plate 5 is guided at one end in a slot 6 formed in the neck 2. The opposite end of the plate is enlarged at 7 and has attached thereto a stem 8 30 slidably in the neck 2 at a point opposite the slot 6. The outer extremity of the stem 8 carries a button 9, and between the button and the neck is a tension spring 10 for a purpose that will presently be described.

An opening 11 is formed in the valve plate 5 40 between the enlargement 7 and the slot 6 and immediately adjacent to the enlargement as clearly shown in Figures 1 and 2. This opening is of the same size as the opening 4 and adapted to register therewith on pushing the button 9, 45 whereupon a free outlet from the interior of the container is formed. The spring 10 normally expands on release of pressure at the button, whereupon the stem 8 and the plate 5 are retracted to the position shown in Figure 2 where the openings 4 and 11 are closed respectively by the members 5 and 3.

For the purposes of description, the movement of the valve plate 5 in the open position shown in Figure 1 will be considered the forward 50 55

movement, and the enlargement 7 will be regarded as being formed on the rear end of the valve plate. The forward space of the enlargement 7 is sloped at 12 away from the closure 3 5 and in the forward direction. From the upper end of the slope, the thickness of the enlargement is gradually reduced as indicated by the numeral 13, thereby correspondingly reducing the resistance of the enlargement to rearward movement and also reducing the packing and compression of the contents between the rear end of the enlargement and the rear side of the neck 2.

The contents of the receptacle may be dense, 15 sluggish or subject to packing. If the plate 5 were uniformly of its minimum thickness, it would slide through the material without directing any of it towards the openings 4 and 11. The material might be so sluggish, dense or compressed as not to flow through the openings, at 20 least not freely. The particular slope of the surface 12, as above described, is such as to direct material towards the openings when the valve plate is moved forward. The slope is important, 25 inasmuch as a mere perpendicular surface or a surface sloping in the opposite direction would either compress the material or move through it without directing material towards the openings.

The action of the slope 12 in directing material to and through the openings accomplishes 30 not only this function but further maintains the openings free of accumulations of packed material that might otherwise fill the openings or interfere with the movement of the valve plate 5 to prevent complete covering of the openings.

Although a specific embodiment of the invention has been illustrated and described, it will be understood that various alterations in the 40 details of construction may be made without departing from the scope of the invention, as indicated by the appended claims.

What I claim is:

1. In a receptacle having a closure on one 45 end, a valve plate slidable on the inner surface of said closure, said closure and plate having each an opening adapted to register one with the other on movement of the plate in the forward direction and to cover one another on movement of the plate in the rearward direction, an 50 enlargement formed on said plate at the rear end of the opening in said plate, said enlargement having its surface at said rear end of said opening sloping forwardly and away from said closure.

2. In a receptacle having a closure on one end, a valve plate slidable on the inner surface of said closure, said closure and plate having each an opening adapted to register one with the other 60 on movement of the plate in the forward direction and to cover one another on movement of the plate in the rearward direction, an enlargement formed on said plate at the rear end of the opening in said plate, said enlargement having its surface at said rear end of said opening sloping forwardly and away from said closure, said enlargement being gradually reduced in thickness in the rearward direction from the 65 free edge of said surface.

3. In a receptacle having a closure on one 70 end, a valve plate slidable on the inner surface of said closure, said closure and plate having

each an opening adapted to register one with the other on movement of the plates in the forward direction and to cover one another on movement of the plate in the rearward direction, an 5 enlargement formed on said plate at the rear end of the opening in said plate, said enlargement having its surface at said rear end of said opening sloping forwardly and away from said closure, a neck formed in said receptacle adjacent to said closure, said neck having a slot 10 receiving and guiding one end of said plate.

4. In a receptacle having a closure on one end, a valve plate slidable on the inner surface of said closure, said closure and plate having each an opening adapted to register one with the other 15 on movement of the plate in the forward direction and to cover one another on movement of the plate in the rearward direction, an enlargement formed on said plate at the rear end of the opening in said plate, said enlargement 20 having its surface at said rear end of said opening sloping forwardly and away from said closure, a neck formed in said receptacle adjacent to said closure, said neck having a slot receiving and guiding one end of said plate, a stem 25 extending from the opposite end of said plate through said neck, a push button on the external end of said neck, and a spring between said button and neck and adapted to move said plate to the closed position.

5. In a receptacle having a closure on one end, a valve plate slidable on the inner surface of said closure, said closure and plate having each an opening adapted to register one with the other on movement of the plate in the forward direction and to cover one another on movement of the plate in the rearward direction, an 35 enlargement formed on said plate at the rear end of the opening in said plate, said enlargement having its surface at said rear end of said opening sloping forwardly and away from said closure, said enlargement being gradually reduced in thickness in the rearward direction from the free edge of said surface, a neck formed 40 in said receptacle adjacent to said closure, said neck having a slot receiving and guiding the forward end of said plate, and a stem extending rearwardly from said enclosure and through said neck.

6. In a receptacle having a closure on one 50 end, a valve plate slidable on the inner surface of said closure, said closure and plate having each an opening adapted to register one with the other on movement of the plate in the forward direction and to cover one another on movement 55 of the plate in the rearward direction, an enlargement formed on said plate at the rear end of the opening in said plate, said enlargement having its surface at said rear end of said opening sloping forwardly and away from said closure, 60 said enlargement being gradually reduced in thickness in the rearward direction from the free edge of said surface, a neck formed in said receptacle adjacent to said closure, said neck having a slot receiving and guiding the forward end 65 of said plate, and a stem extending rearwardly from said enclosure and through said neck, a push button on the external end of said neck, and a spring between said button and neck and adapted to move said plate to the closed position.

GÉRARD LAPIERRE.
